CLAIM

The ornamental design for transceiver base, as shown and described.

DESCRIPTION

FIG. 1 is a front perspective view of the transceiver base showing my the new design.

FIG. 2 is a back perspective view of the transceiver base.

FIG. 3 is a front view of the transceiver base.

FIG. 4 is a back view of the transceiver base.

FIG. 5 is a top plan view of the transceiver base.

FIG. 6 is a left side view of the transceiver base.

FIG. 7 is a right side view of the transceiver base; and,

FIG. 8 is a bottom plan view of the transceiver base.

1 Claim, 5 Drawing Sheets

FIG. 1

FIG. 2

FIG. 3

FIG. 4

FIG. 5

FIG. 8

FIG. 6

FIG. 7

UNITED STATES PATENT AND TRADEMARK OFFICE
CERTIFICATE OF CORRECTION

PATENT NO. : Des 437,844 S
DATED : February 20, 2001
INVENTOR(S) : Ian Leslie Sayers, Michael Allan Neiman and Richard William Benner

Page 1 of 1

It is certified that error appears in the above-identified patent and that said Letters Patent is hereby corrected as shown below:

Description,
Line 2, delete "my".

Signed and Sealed this

Sixth Day of November, 2001

Attest:

Nicholas P. Godici

Attesting Officer

NICHOLAS P. GODICI
Acting Director of the United States Patent and Trademark Office
